UNITED STATES PATENT OFFICE.

WALTER SCOTT, OF PLAINFIELD, NEW JERSEY.

PRINTING-MACHINE.

SPECIFICATION forming part of Letters Patent No. 790,531, dated May 23, 1905.

Application filed August 2, 1901. Serial No. 70,634.

To all whom it may concern:

Be it known that I, WALTER SCOTT, a citizen of the United States, and a resident of Plainfield, in the county of Union and State of New Jersey, have invented certain new and useful Improvements in Printing-Machines, of which the following is a specification.

My invention relates generally to printing-machines, and more especially to the means which impart movement to the reciprocating bed carrying the type.

This is a companion application to the one filed by me jointly with Eugene W. Swindells on the 15th day of April, 1901, and bearing Serial No. 55,820, in which is shown a printing-machine whose impression-cylinder makes one revolution to each reciprocation of the type-bed.

In the present application is shown a machine in which the impression-cylinder makes two revolutions to each reciprocation, but which is otherwise, with the exceptions hereinafter noted, of the same general construction as the machine shown in the application above noted.

The objects of this invention are the same as the objects of the invention described in the companion application above named and may be briefly stated to be the production of a superior reversing mechanism and the reduction of the number of gears used between the impression-cylinder and the type-bed.

I shall describe a printing-machine embodying my invention and afterward point out the novel features in the claims.

In the drawings I have embodied my invention in a suitable mechanism, it being of course obvious that changes may be made within the scope of the claims.

Figure 1 is a side view of a two-revolution printing-machine embodying my invention, the type-bed being shown at the end of its reciprocation, parts being also omitted and indicated diagrammatically for the sake of clearness. Fig. 2 is an end view of Fig. 1 looking in the direction of the arrow z , the gear which operates the reciprocating bed being shown in mesh with the upper rack. Parts are also omitted in this view to facilitate clearness of illustration. Fig. 3 is a detail view of the

bed-racks, driving-gear, and adjacent elements. Fig. 4 is a sectional detail view on the line x - x of Fig. 1 and also looking in the direction of the arrow z , showing the means for rotating the gear engaging with the racks in a position corresponding to the position of the elements in Fig. 2. Fig. 5 is a detail view showing the means for vibrating the rack-gear. Fig. 6 is a sectional view on the line y - y of Fig. 3.

Throughout the specification like characters of reference denote corresponding elements.

A represents the framework of the machine, on which is mounted on suitable bearings a' the impression-cylinder B, vibrated by means of the toggles b' once to every two revolutions in a well-known manner. The type-bed C is mounted on frictional rollers c' , which are carried by and slide upon the tracks c^2 . Underneath the type-bed C and bolted to it is a rack-hanger G. On this rack-hanger are mounted the upper rack g' and the lower rack g^2 and further segmental racks g^3 , g^9 and g^{10} . On each end of the rack-hanger is also a rigid shoe g^5 and a bearing-shoulder g^6 , forming a slot curved to correspond with the pitch-line of the segmental racks g^3 and g^4 .

On the end of the shaft b^2 of the impression-cylinder B is mounted a large gear b^3 , underneath and engaging with which is mounted the gear D, supported on the bushing or fixed hub d' , bolted to the framework and of a diameter properly proportioned to the diameter of the gear on the impression-cylinder shaft. Adjacent to one side of the gear D is the driving-pinion E, which is fastened to the driving-shaft e' , which also carries the belt-pulleys e^2 and e^3 , transmitting motion to the machine.

The bushing d' , on which the gear D rotates, is hollow and affords a bearing for the eccentrically-located rock-shaft F, extending in toward the center of the machine. This eccentric rock-shaft F has an eccentric hole f' and is supported at its other end by the bearing f^2 . Inside the eccentric rock-shaft or sleeve F is placed the shaft M, which of course thereby also becomes eccentric with relation to the gear D. On the shaft M is the

gear-wheel m' , adapted to engage with the racks g' and g^2 . The gear m' is preferably of a circumference equal to the uniform travel of the bed in one direction. By this means 5 the gear m' makes three revolutions to each complete back-and-forth movement of the bed. Fastened to one side of the gear m' is the pinion m^2 . This pinion m^2 is preferably made of a diameter equal to one-half the diameter of the gear m' plus one-half the distance which the said gear raises or lowers to engage and disengage with the racks g' and g^2 . Immediately adjacent to the pinion m^2 is the circular bearer m^3 of a diameter equal to the 15 pitch-diameter of the pinion m^2 . On the gear m' is also placed a stud m^4 , on which revolves a friction-roll m^5 . This roll m^5 is preferably placed at one side of the pinion m^2 and the circular bearer m^3 and at a point between their 20 pitch-lines and centers, the preferred position being half-way. This position of the roll, as pointed out in the companion application hereinbefore referred to, makes the path of the roll such that it enables the said roll to 25 engage with its corresponding element on the bed—in this case the shoe g^5 —a considerable length of time if the preponderance of pressure is in that direction. The result of this is that the said shoe g^5 and the roll will control 30 the bed during its reversal. On the outer end of the shaft M is fastened an arm m^6 , carrying a guideway m^7 . The gear-wheel D carries a pin d^5 , having a block d^6 , which extends into the guideway m^7 , thereby driving the 35 shaft M .

Inside the framework is mounted the cam R , having the gear r' connecting, through the pinion r^2 and the gear r^3 , with the gear D and geared to make one revolution with each 40 reciprocation of the type-bed and with every two revolutions of the impression-cylinder. Fastened to the framework is the crank-arm S , carrying the friction-rolls s' , adapted to engage with the cam R . On the hollow eccentric 45 shaft or sleeve F and integral therewith or fastened thereto is an arm f^5 . This arm f^5 and the crank-arm S are connected by means of the connecting-rod s^2 , thereby causing the cam R to rock the eccentric rock-shaft F periodically.

The operation is as follows: When the end of the rack g^2 approaches the point of contact with the gear m' and is about to leave the same, the pinion m^2 engages with the 55 curved rack g^9 , continuing the forward movement until the roll m^5 engages with the shoe g^5 . This roll m^5 engaging with the shoe g^5 and the circular bearer m^3 engaging with the bearing-shoulder g^6 control the endwise 60 movement of the bed, pinion m^2 and rack g^9 continuing the movement until the gear m' is in mesh with the upper rack g' . During this operation the gear m' has changed its position in contact with the rack g^2 to a position 65 in contact with the rack g' by means of

the shaft M , on which it is mounted, being raised a sufficient distance by the movement of the eccentric rock-shaft or sleeve F , actuated by the cam R . When the other end of the rack g' reaches the gear m' , the operation 70 is again repeated and the gear m' lowered, so as to disengage with the rack g' and engage with the rack g^2 .

It is not essential that the pinion m^2 should be a complete gear when separate and disconnected racks like g^3 and g^4 are used; but when intermediate teeth are added, so as to keep the said pinion in mesh all the way, it is of course necessary that it should be a complete gear. The construction of the curved 80 racks at the end with intermediate teeth added is not a necessity, but merely a matter of convenience to keep the gear m^2 in mesh all the way round. These intermediate teeth are indicated in dotted lines in Fig. 3 of the 85 drawings. The exact shape of the segments at the end of the bed and auxiliary gear need, of course, not be followed. It is only necessary that the segments and the pinion should be of a sufficient length and shape to engage 90 with each other until the bed has moved far enough to allow the roll m^5 and the bearer m^3 to engage, respectively, with the shoe g^5 and the shoulder g^6 . Furthermore, as has been stated herein, the shaft M is eccentric 95 with relation to the gear D in the eccentric sleeve F in order that by the shifting of the said eccentric sleeve by the cam R it may be moved up and down to enable the gear m' to engage with the upper and lower rack and at 100 the same time be rotated by the said gear D ; but when the eccentric sleeve F is moved to the position shown in Fig. 4 the eccentrically-located shaft M is concentric with relation to the gear D . This oscillation of the eccentric 105 sleeve F of course also changes the position of the guide m^7 with relation to the pin d^5 , so that the distance which the block d^6 has to travel in a given time varies, thereby causing a variation in its speed, and consequently in 110 the speed of the shaft M . When the shaft M is concentric with the gear D , the speed of the said shaft, and consequently of the bed, will be the same speed as the speed of the impression-cylinder, and the elements must 115 of course be so constructed or timed that the said shaft is in its concentric position with relation to the gear D when the machine is in the act of printing, so that the impression-cylinder and type-bed will move at the same 120 surface speed.

The diameter of the pinion m^2 should be substantially one-half the diameter of the gear m' plus one-half the distance the said gear raises and lowers. It could be larger 125 or smaller than this relative to the gear m' ; but this construction is preferred, as it is thereby possible to make the segmental racks appear as continuations of the straight racks, as shown in the drawings.

Having thus described my invention, what I claim is—

1. A reciprocating bed supporting two racks, two gear-segments at each end, two bearing-shoulders and two shoes forming two slots, in combination with a driving-gear to engage alternately with the racks, an auxiliary gear to engage with the gear-segments, and a bearer and a roll to engage respectively with the bearing-shoulders and with the shoes to reverse the motion of the bed, and to control it while turning.

2. The combination of a reciprocating bed supporting two racks, two gear-segments at each end, two bearing-shoulders and two shoes forming two slots, a driving-shaft having thereon a gear to engage with the racks, an auxiliary gear to engage with the gear-segments, a bearer and a roll to engage respectively with the bearing-shoulders and with the shoes to reverse the motion of the bed, and to control it while turning, and means for raising and lowering the shaft after the ends of the racks have reached the gear.

25 3. The combination of a frame carrying two racks, two gear-segments at each end, two bearing-shoulders and two shoes forming two slots, a driving-gear caused to engage alternately with the racks, an auxiliary gear of a lesser diameter attached to the driving-gear to engage with the segments, and a bearer and a roll, the latter placed a distance inside the pitch-line of the auxiliary gear, to engage respectively with the bearing-shoulders and with the shoes to reverse the motion of the bed, and to control it while turning.

40 4. The combination of a frame carrying two racks, two gear-segments at each end, two bearing-shoulders and two shoes forming two slots, a driving-gear caused to engage alternately with the racks, an auxiliary gear or gear-segment of a diameter somewhat greater than the radius of the driving-gear attached to the latter and adapted to engage with the segments, and a bearer, of the same diameter as the auxiliary gear, and a roll, placed at a point intermediate the center and the pitch-line of the auxiliary gear, to engage respectively with the bearing-shoulders and with the 45 shoes to reverse the motion of the bed, and to control it while turning.

55 5. The combination of a frame carrying two racks, two gear-segments at each end, two bearing-shoulders and two shoes forming two slots, a driving-gear caused to engage alternately with the racks, means for raising and lowering the driving-gear after the ends of the racks have reached the said gear, an auxiliary gear or gear-segment of a diameter equal to one-half the diameter of the driving-gear plus substantially one-half the distance the said gear is raised or lowered carried by the said driving-gear to engage with the segments, and a bearer, of the same diameter as 60 the auxiliary gear, and a friction-roll, carried

inside of the pitch-line of the auxiliary gear, to engage respectively with the bearing-shoulders and with the shoes, to reverse the motion of the bed, and to control it while turning.

6. The combination of a frame carrying two racks, two gear-segments at each end, two bearing-shoulders and two shoes forming two slots, a driving-gear caused to engage alternately with the racks, an auxiliary gear of a lesser diameter attached to the driving-gear to engage with the segments, and a bearer and a roll, the latter carried at a point substantially half-way between the pitch-line and the center of the auxiliary gear, to engage respectively with the bearing-shoulders and with the shoes to reverse the motion of the bed, and to control it while turning.

7. The combination of a frame carrying two racks, two gear-segments at each end, two bearing-shoulders and two shoes forming two slots, a driving-gear caused to engage alternately with the racks, means for raising and lowering the driving-gear after the ends of the racks have reached the said gear, an auxiliary gear or gear-segment of a diameter equal to one-half the diameter of the operating-gear plus substantially one-half the distance the said gear is raised or lowered carried by the said driving-gear to engage with the segments, and a bearer and a friction-roll, the latter carried at a point substantially half-way between the pitch-line and the center of the said auxiliary gear, to engage respectively with the bearing-shoulders and with the shoes to reverse the motion of the bed, and to control it while turning.

8. The combination of a frame carrying two racks, two gear-segments at each end, two bearing-shoulders and two shoes forming two slots, a driving-gear caused to engage alternately with the racks, an auxiliary gear of a lesser diameter attached to the driving-gear to engage with the segments, a bearer and a roll, the latter placed a distance inside of the pitch-line of the auxiliary gear, to engage respectively with the bearing-shoulders and with the shoes to reverse the motion of the bed, and to control it while turning, and means to raise and lower the driving-gear after the ends of the racks have reached the said gear.

9. The combination of a frame carrying two racks, two gear-segments at each end, two bearing-shoulders and two shoes forming two slots, a driving-gear caused to engage alternately with the racks, an auxiliary gear of a lesser diameter attached to the driving-gear to engage with the segments, and a bearer and a roll, the latter placed at a point intermediate the center and the pitch-line of the auxiliary gear, to engage respectively with the bearing-shoulders and with the shoes, to reverse the motion of the bed, and to control it while turning.

10. The combination of a frame carrying two racks, two gear-segments at each end, two

bearing-shoulders and two shoes forming two slots, a driving-gear caused to engage alternately with the racks, an auxiliary gear of a lesser diameter attached to the driving-gear 5 to engage with the segments, a bearer and a roll, the latter placed at a point intermediate the center and the pitch-line of the auxiliary gear, to engage respectively with the bearing-shoulders and with the shoes to reverse the 10 motion of the bed, and to control it while turning, and means to raise and lower the driving-gear after the ends of the racks have reached the said gear.

11. The combination of a frame carrying 15 two racks, two gear-segments at each end, two bearing-shoulders and two shoes forming two slots, an auxiliary gear or gear-segment of a diameter somewhat longer than the radius of the driving-gear attached to the latter to engage 20 with the segments, a bearer and a roll, the latter of which is placed at a point intermediate the center and pitch-line of the auxiliary gear, to engage respectively with the shoes to reverse the motion of the bed, and 25 to control it while turning, and means to raise and lower the driving-gear after the ends of the racks have reached the said gear.

12. The combination of a reciprocating body, an upper and lower rack on same, a 30 driving-gear adapted to engage alternately with said racks to reciprocate the body, a bearing-shoulder and a rigid shoe at each end of the racks forming a slot, a bearer and a friction-roll carried by the gear adapted to engage 35 respectively with the bearing-shoulders and the shoes to reverse the motion of the bed, and to control it while turning, two rack-segments at each end carried by said body, and an auxiliary gear or segment carried by the 40 driving-gear adapted to coact with the said rack-segments after the racks disengage the driving-gear and before the roll engages the shoes or vice versa.

13. The combination of a gear-wheel, a 45 bushing forming a hub or shaft for the said gear-wheel, a rock-shaft located eccentrically in said bushing and having a longitudinal eccentric hole, a rotatable shaft resting therein, a guide on the end of the rotatable shaft and 50 an arm carrying a block on the gear-wheel adapted to engage with the guide to impart the motion of the gear to the rotatable shaft.

14. The combination of a gear-wheel, a 55 bushing forming a hub or shaft for the said gear-wheel, a rock-shaft located eccentrically in said bushing and having a longitudinal eccentric hole, a rotatable shaft resting therein, a guide on the end of the rotatable shaft, and an arm carrying a block on the gear-wheel 60c adapted to engage with the guide to impart the motion of the gear to the rotatable shaft, a cam making one revolution to each impression, and connections between the cam and the rock-shaft whereby the rock-shaft is op-

erated periodically by the movement of the 65 cam.

15. In a printing-machine, the combination of an impression-cylinder making two revolutions to each impression, a reciprocating type-bed, a rock-shaft, an eccentrically-located rotatable shaft resting in said rock-shaft, means for operating the reciprocating bed from the rotatable shaft, a gear mounted on a fixed hub at the end of the rock-shaft and eccentrically thereto imparting motion to 70 the impression-cylinder and to the rotatable shaft, a cam making one revolution to each impression, and means operated by said cam for rocking the shaft periodically.

16. In a printing-machine, the combination 80 of an impression-cylinder making two revolutions to each impression, a reciprocating type-bed, a rock-shaft, an eccentrically-located rotatable shaft resting in said rock-shaft, means for operating the reciprocating 85 bed from the rotatable shaft, a gear mounted on a fixed hub at the end of the rock-shaft and eccentrically thereto imparting motion to the impression-cylinder and to the rotatable shaft, a cam making one revolution to each 90 impression, suitable gearing connecting said cam with the gear on the hub, and means operated by said cam for rocking the shaft periodically.

17. In a printing-machine, the combination 95 of an impression-cylinder making two revolutions to each impression, a reciprocating type-bed, a rock-shaft, an eccentrically-located rotatable shaft resting in said rock-shaft, means for operating the reciprocating 100 bed from the rotatable shaft, a gear mounted on a fixed hub at the end of the rock-shaft and eccentrically thereto imparting motion to the impression-cylinder and to the rotatable shaft, a cam located inside the framework and 105 making one revolution to each impression, suitable gearing connecting said cam with the gear on the hub, and means operated by said cam for rocking the shaft periodically.

18. In a printing-machine, the combination 110 of a reciprocating type-bed carrying two racks, two rack-segments at each end, two bearing-shoulders and two rigid shoes forming two slots, a driving-gear for engaging with the racks carrying an auxiliary gear for 115 engaging with the segments, a bearer for engaging with the bearing-shoulders, and a roll for engaging with the shoes, the co-operation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said 120 hole, and means for periodically operating the rock-shaft to raise and lower the rotatable shaft after the ends of the racks have reached the driving-gear.

19. In a printing-machine, the combination of a reciprocating type-bed carrying two racks, two rack-segments at each end, two bearing-shoulders and two rigid shoes forming two slots, a driving-gear for engaging with the racks carrying an auxiliary gear for engaging with the segments, a bearer for engaging with the bearing-shoulders, and a roll for engaging with the shoes, the coöperation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said hole, and means for periodically operating the rock-shaft to raise and lower the rotatable shaft after the driving-gear is disengaged from the upper or lower rack. 5
20. In a printing-machine, the combination of a reciprocating type-bed carrying two racks, two rack-segments at each end, two bearing-shoulders and two rigid shoes forming two slots, a driving-gear for engaging with the racks carrying an auxiliary gear for engaging with the segments, a bearer for engaging with the bearing-shoulders, and a roll for engaging with the shoes, the coöperation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said hole, and means for periodically operating the rock-shaft to raise and lower the rotatable shaft after the driving-gear is disengaged from the upper or lower rack. 10
21. In a printing-machine, the combination of a reciprocating type-bed carrying two racks, two rack-segments at each end, two bearing-shoulders and two rigid shoes forming two slots, a driving-gear for engaging with the racks carrying an auxiliary gear for engaging with the segments, a bearer for engaging with the bearing-shoulders, and a roll for engaging with the shoes, the coöperation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said hole, and means for periodically operating the rock-shaft to raise and lower the rotatable shaft while the motion of the bed is being reversed. 15
22. In a printing-machine, the combination of a reciprocating type-bed carrying two racks, two rack-segments at each end, two bearing-shoulders and two rigid shoes forming two slots, a driving-gear for engaging with the racks carrying an auxiliary gear for engaging with the segments, a bearer for engaging with the bearing-shoulders, and a roll for engaging with the shoes, the coöperation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said hole, means for periodically operating the rock-shaft to raise and lower the rotatable shaft after the driving-gear is disengaged from the upper or lower rack. 20
23. In a printing-machine, the combination of a reciprocating type-bed carrying two racks, two rack-segments at each end, two bearing-shoulders and two rigid shoes forming two slots, a driving-gear for engaging with the racks carrying an auxiliary gear for engaging with the segments, a bearer for engaging with the bearing-shoulders, and a roll for engaging with the shoes, the coöperation of the said bearer and roll with the said bearing-shoulders and shoes reversing the motion of the bed and controlling it while turning, a rotatable shaft mounting said driving-gear, a rock-shaft having a longitudinal eccentric hole, the rotatable shaft resting in said hole, a gear mounted on a fixed hub at the end of the rock-shaft and eccentrically thereto, an impression-cylinder making two revolutions to each impression meshing with said gear on the hub, and means for operating the rotatable shaft from the gear on the hub. 25
24. A reciprocating bed supporting two main racks two bearing-shoulders and two shoes forming two slots, in combination with a driving-gear arranged to engage alternately with the main racks to reciprocate the said bed and a bearer and a roll to engage respectively with the bearing-shoulders and with the shoes to reverse the motion of the bed, and to control it while turning, curved racks located intermediate the main racks and the shoes, and an auxiliary gear carried by the driving-gear to engage with the curved racks. 30
25. A reciprocating bed supporting two main racks, two bearing-shoulders and two shoes forming two slots, in combination with a driving-gear arranged to engage alternately with the main racks to reciprocate the said bed, and a bearer and a roll to engage respectively with the bearing-shoulders and with the shoes to reverse the motion of the bed, and to control it while turning, curved racks located intermediate the main racks and the shoes, intermediate teeth connecting the curved racks at each end, and an auxiliary gear carried by 35

the driving-gear to engage with the curved racks.

26. The combination of a reciprocating body carrying two main racks, two bearing-shoulders and two shoes forming two slots, a driving-shaft having thereon a driving-gear to engage with the main racks to reciprocate the said body and a bearer and a roll to engage respectively with the bearing-shoulders and with the shoes to reverse the motion of the bed, and to control it while turning, curved racks located intermediate the main racks and the shoes, an auxiliary gear carried by the driving-gear to engage with the curved racks, and means to raise and lower the shaft after the ends of the racks have reached the driving-gear.

27. The combination of a reciprocating body carrying two main racks, two bearing-shoulders and two shoes forming two slots, a driving-shaft having thereon a driving-gear to engage with the main racks to reciprocate the said body and a bearer and a roll to engage respectively with the bearing-shoulders and with the shoes to reverse the motion of the bed, and to control it while turning, curved racks located intermediate the main racks and the shoes, intermediate teeth connecting the curved racks at each end, an auxiliary gear

carried by the driving-gear to engage with the curved racks, and means to raise and lower the shaft after the ends of the racks have reached the driving-gear.

28. The combination of a reciprocating body, an upper and a lower rack on same, a driving-gear adapted to engage alternately with the said racks to reciprocate the body, a bearing-shoulder and a shoe at each end of the racks forming a slot, a bearer and a roll carried by the gear adapted respectively to engage therewith to reverse the motion of the bed, and to control it while turning; two rack-segments at each end carried by said body located intermediate the racks and the shoes, intermediate teeth connecting the rack-segments at each end, and an auxiliary gear carried by the driving-gear adapted to coact with the said rack-segment to continue the movement of the bed after the racks disengage the driving-gear and before the roll engages the shoes or vice versa.

Signed at New York, in the county of New York and State of New York, this 3d day of July, A. D. 1901.

WALTER SCOTT.
